STEPLADDER

Ned L. Thrasher, Perrysburg, N. Y.

Application November 4, 1933, Serial No. 696,721

3 Claims. (Cl. 228—59)

This invention relates to step ladders and more especially to means whereby the steps of the ladder can be reinforced and also held properly assembled with the stiles.

5 It is an object of the invention to provide a truss of novel construction for use in connection with a step, the rod of the truss also serving as a means for properly tying the ends of the step to the stiles.

10 Another object is to provide a structure which acts to relieve the stiles from strains at any points other than at the ends of the step supporting a weight.

A still further object is to extend the end portions of the truss rod through bores in the ends of the step whereby weakening of the parts such as would result from grooving them, is eliminated.

A still further object is to provide a truss rod which, by extending through bores in both the 20 step and the stiles is positively prevented from working downwardly in the stiles and pulling away from the step with which it is associated.

Another object is to provide the truss with a spacing block which acts to brace the step 25 throughout its width so as to prevent the step from rocking or sagging transversely and ultimately checking or splitting.

A further object is to provide a truss construction which, because of its location, does not trans- 30 fer any of the strains from one step to any other step or truss in the ladder and positively prevents any relative movement of the interfitting parts.

With the foregoing and other objects in view which will appear as the description proceeds, 35 the invention consists of certain novel details of construction and combinations of parts herein- after more fully described and pointed out in the claims, it being understood that changes may be made in the construction and arrangement of 40 parts without departing from the spirit of the invention as claimed.

In the accompanying drawing the preferred form of the invention has been shown.

In said drawing:

45 Figure 1 is a front elevation of a portion of a step ladder showing a step provided with the present improvements.

Figure 2 is a section on line 2—2, Figure 1.

Figure 3 is a section on line 3—3, Figure 1.

50 Figure 4 is a section on line 4—4, Figure 1.

Figure 5 is an enlarged section through one side portion of the ladder on the line 5—5, Figure 2.

Referring to the figures by characters of refer- 55 ence 1 designates the stiles of a step ladder which

are provided with the usual transverse grooves 2 in their inner faces providing seats for the ends of a step 3. Extending through each stile is a bore 4 which opens into the center of the groove 2 and registers with the outer end of an inclined bore 5 formed in the end portion of step 3 and opening downwardly through the bottom of the step.

Secured to the step 3 at its center is a trans- 60 versely extending block 6 constituting a reinforcement. This block can extend to the edges of the step or can terminate desired distances inwardly therefrom. The center of the bottom of the block has a groove 7 providing a seat for the center portion of a truss rod 8. This rod is 65 inclined upwardly in opposite directions respectively from the block and is seated snugly in the inclined bores 5 and the ends of the rod are extended outwardly through the bores 4 in the stiles. These ends are screw threaded for en- 70 gagement by nuts 9 and, if desired, reinforcing plates 10 can be secured to the outer faces of the stiles. These plates have holes 11 through 75 which the rod extends and as the plates provide seats for the nuts, the stiles will be protected 80 against wear which might result from direct contact of the nuts therewith.

Attention is called to the fact that the bores 4 and 5 come together at points midway between the top and bottom faces of step 3. Thus a 85 wedge-shaped section 12 of the step is left beneath each bore and this serves to support the rod at the correct angle within the step and stile and also acts as a means for preventing the rod from pulling downwardly on the stile, enlarging 90 the openings 4, and splitting the stile and pulling away from the step.

The rod 8 acts as a tie for binding the stile directly against the end of the step and as the compression is along the center of the step, the 95 parts will be held tightly against relative movement and no strains will be distributed to other steps or to parts of the stiles between the steps. Consequently the resultant step ladder construc- 100 tion is stronger and more durable than would be possible through other arrangements of a truss rod.

The block 6 supports the middle portion of the step substantially throughout its width. Thus the step is held against rocking under a load 105 and will not check or crack.

What is claimed is:

1. A ladder construction including stiles hav- 110 ing transverse grooves providing seats, there being a bore extending through each stile and open-

ing into the center of its groove, a step seated snugly at its ends within the grooves, there being an upwardly and outwardly inclined bore in each end portion of the step opening through the end 5 of the step at a point between the upper and lower faces of the step and registering with the adjacent bore in the stile, a portion of the step forming a wedge-like area between the inclined bore and the bottom of the step, which area extends into the groove, a truss rod having upwardly diverging portions extending through the bores in the steps and outwardly extended portions 10 projecting through the bores in the stile, spacing means between the rod and the step, and fastening means engaging the ends of the rod for tightening the grooved portions of the stiles against the ends of the step.

2. A ladder construction including stiles having transverse grooves providing seats, there being a bore extending through each stile and opening into the center of its groove, a step seated snugly at its ends within the grooves, there being an upwardly and outwardly inclined bore in each end portion of the step opening through the end 15 of the step at a point between the upper and lower faces of the step and registering with the adjacent bore in the stile, a portion of the step forming a wedge-like area between the inclined bore and the bottom of the step, which area extends into the groove, a truss rod having upwardly 20 diverging portions extending through the bores in the steps and outwardly extended portions projecting through the bores in the stile, spacing means between the rod and the step, and fastening means engaging the ends of the rod for 25 tightening the grooved portions of the stiles against the ends of the step.

3. A ladder construction including stiles having transverse grooves providing seats, there being a bore extending through each stile and opening into the center of its groove, a step seated snugly at its ends within the grooves, there being an upwardly and outwardly inclined bore in each end portion of the step opening through the end 30 of the step at a point between the upper and lower faces of the step and registering with the adjacent bore in the stile, a portion of the step forming a wedge-like area between the inclined bore and the bottom of the step, which area extends into the groove, a truss rod having upwardly diverging portions extending through the bores in the steps and outwardly extended portions 35 projecting through the bores in the stile, spacing means between the rod and the step, and fastening means engaging the ends of the rod for 40 tightening the grooved portions of the stiles against the ends of the step, said spacing means being extended transversely along the under-side of the step to transmit downward thrust to the rod from the step.

means between the rod and the step, and fastening means engaging the ends of the rod for tightening the grooved portions of the stiles against the ends of the step, said spacing means being extended transversely along the under-side of 80 the step to transmit downward thrust to the rod from the step.

3. A ladder construction including stiles having transverse grooves providing seats, there being a bore extending through each stile and opening into the center of its groove, a step seated snugly at its ends within the grooves, there being an upwardly and outwardly inclined bore in each end portion of the step opening through the end of the step at a point between the upper and lower faces of the step and registering with the adjacent bore in the stile, a portion of the step forming a wedge-like area between the inclined bore and the bottom of the step, which area extends into the groove, a truss rod having upwardly 85 diverging portions extending through the bores in the steps and outwardly extended portions projecting through the bores in the stile, spacing means between the rod and the step, and fastening means engaging the ends of the rod for 90 tightening the grooved portions of the stiles against the ends of the step, said spacing means being extended transversely along the under-side of the step to transmit downward thrust to the rod from the step, and wear devices interposed 95 between the stiles and the fastening means.
